UNITED STATES PATENT OFFICE.

WILLIAM E. CRANE AND CHARLES D. PRATT, OF BINGHAMTON, NEW YORK.

GASOLENE SOLDERING-TOOL.

No. 872,500.

Specification of Letters Patent.

Patented Dec. 3, 1907.

Application filed July 18, 1906, Serial No. 326,761.

To all whom it may concern:

Be it known that we, WILLIAM E. CRANE and CHARLES D. PRATT, citizens of the United States, residing at Binghamton, in the county of Broome and State of New York, have invented a new and useful Improvement in a Gasolene Soldering-Tool, of which the following is a specification.

This invention relates to soldering irons and more particularly to gasolene heated soldering irons, the object being to provide a soldering iron so constructed that the flow of gasolene will be regulated so that a uniform blast is obtained at all times.

Another object of my invention is to provide the gasolene reservoir with a pump so that air can be mixed with the gasolene so as to give a strong blast when using as a torch.

With these objects in view, the invention consists in the novel features of construction, combination and arrangement of parts hereinafter fully described and pointed out in the claims.

In the drawing forming a part of this specification:—Figure 1 is a perspective view of our improved soldering iron showing a part of the reservoir covered with non-conducting material. Fig. 2 is an enlarged longitudinal sectional view of the same. Fig. 3 is a section taken on lines 3—3 of Fig. 2. Fig. 4 is a section taken on lines 4—4 of Fig. 2. Fig. 5 is a detail top plan view of a portion of the same partly in section. Fig. 6 is a longitudinal sectional view of a portion of the oil chamber showing the pump in section. Fig. 7 is a detail sectional view of the pump valve.

Referring to the drawing A indicates a generator head formed of a flanged cap provided with oppositely disposed feet A', so as to hold the same in a vertical position, the flange of the cap being internally screw-threaded. The cap is provided with a vertical enlargement A², provided with an oil cup A³, projecting out from its top having an outwardly projecting hook A⁴, so that it can be hung up when desired. A central bore A⁵, is formed in the enlargement, reduced and threaded at its upper end and communicating with a threaded opening A⁶, at its bottom, extending through the cap in which the threaded end B', of a tube B is secured. A threaded opening A⁷, is formed in the cap over the opening A⁶, in which is secured the threaded end C', of a bar C which is provided with a bifurcated end C², and a reduced portion C³.

Pivoted in the bifurcated end C², of the rod

C is the reduced end D', of a weight D provided with a groove D², so that it can swing over the tube B. An arm D³, projects out from the weight D on which the bifurcated end E', of a valve-stem E is pivoted, the bifurcated end of the stem is adapted to work over the reduced portion C³, of the bar C, so as to hold said valve stem in a vertical position. The stem E is provided with a pointed end E², adapted to be seated in a tapering opening B², forming a valve-seat, in the tube B.

Secured in the threaded flange of the top of the generator head A is the threaded end 70 of a tube F, which is provided with an oppositely threaded end on which is secured a threaded flanged cap G provided with a threaded opening having an outwardly projecting flange G', in which the threaded portion of the cylinder H is secured by a nut I, carrying a rubber washer I', adapted to engage the flange G', of the cap G. A cap J, is secured on the end of the threaded portion of the cylinder H, provided with a piston head 80 K'. The end of the cylinder H, is provided with a nozzle H', and outwardly projecting spaced rods L, provided with nuts L', and surrounded by coil-springs L², arranged between cross bars L³, L⁴, slidably mounted 85 thereon. The cross bar L⁴, has a rod extending through an opening in the bar L³, and is provided with a pocket in which is secured a rubber packing L⁵, adapted to engage the nozzle H', and close the same so 90 that air can be pumped into the gasolene reservoir formed by the tube and caps.

Secured in the reduced threaded end of the bore A⁵ is the threaded end of the pipe M, which carries a perforated shell N, forming a 95 mixing chamber controlled by a needle valve O. Secured to the end of the shell N is a perforated shell P, forming a combustion chamber which is provided with a square opening in its end in which soldering irons Q 100 are adapted to be secured by set screws P', so that the point can be readily removed and the iron used for a torch when desired.

The operation is as follows:—The oil reservoir is filled with gasolene and the pump is 105 operated a few times, then the needle valve is opened and the oil cup is filled with gaso lene and the valve is then cut off and the gasolene ignited heating the mixing and combustion chamber. The needle valve is 110 then turned on and a perfect blue flame will be obtained in the combustion chamber.

It will be readily seen that the gasolene will be fed through the end of the tube when held in a horizontal position and through the opening in the tube when tilted downwardly 5 as the weight will open the valve and allow the gasolene to flow therethrough, thereby causing an even flow of gasolene and obtaining a uniform blast.

A covering R of non-conducting material 10 is placed on the tube F so that the reservoir will be protected from the cold in winter and the heat in summer, and at the same time forming a handle for the tube.

Having thus fully described our invention 15 what we claim as new and desire to secure by Letters Patent is:—

1. In a gasolene soldering iron, the combination with a reservoir provided with a tube having an opening formed adjacent one 20 end, of a mixing and combustion chamber communicating with one end of said tube, a weight pivoted in said reservoir over said tube provided with an arm, and a valve stem having a bifurcated upper end pivoted to an 25 arm of said weight directly over said tube, substantially as described.

2. In a gasolene soldering iron, the com-

bination with a reservoir provided with a cap at the rear end carrying a pump, of a cap formed on the forward end and provided with an enlargement having a vertical bore, 30 a tube extending within said reservoir communicating with said bore and provided with an opening adjacent its fixed end, a mixing and combustion chamber connected to said bore and controlled by a needle valve, an oil 35 cup formed on the enlargement of said cap directly under said mixing and combustion chamber forming an auxiliary heater, said oil cup having a downwardly curved hook projecting therefrom a bar secured to the 40 forward cap of the reservoir and having a bifurcated end, a weight pivoted within said reservoir to the bifurcated end of said bar, directly over said tube, and a valve stem having a bifurcated upper end pivoted to an 45 arm of said weight directly over said tube, substantially as described.

WILLIAM E. CRANE.
CHARLES D. PRATT.
